UNITED STATES PATENT OFFICE

ANTONE TANDLER, OF CHICAGO, ILLINOIS.

STEAM-ENGINE VALVE.

SPECIFICATION forming part of Letters Patent No. 645,194, dated March 13, 1900.

Application filed May 8, 1899. Serial No. 715,961. (No model.)

To all whom it may concern:

Be it known that I, ANTONE TANDLER, a citizen of the United States, residing at Chicago, in the county of Cook and State of Illinois, have invented certain new and useful 5 Improvements in Steam-Engine Valves, of which the following is a specification.

In large high-speed double-acting engines difficulty is encountered in quickly removing 10 the exhaust-steam from the cylinder, the ordinary steam-valve mechanism not presenting an exhaust-opening of sufficient area to permit of the easy escape of the exhaust-steam. By reason of this imperfect operation 15 of the steam-valve the exhaust-steam must be considerably compressed in the cylinder by the returning piston in order that it may be forced through the inadequate exhaust-ports, whereby the mechanical parts of the 20 engine are strained and the economy of its operation and the efficiency of its performance are impaired. To overcome these objections and remedy the defects indicated are among the objects of this invention; and these objects are attained by the production of a piston-valve having auxiliary exhaust-ports, by 25 means of which the area of the exhaust-port is largely increased and said exhaust quickly opened.

30 While the valve herein described is particularly adapted to high-speed engines, it is economically applicable to powerful low-speed engines where a large quick-acting exhaust is desirable.

35 In the accompanying drawings, Figure 1 is a longitudinal vertical central section through the steam-chest, showing the parts in position for the admission of steam to the front end of the engine-cylinder and showing the 40 piston in said cylinder at the forward end of its stroke. Fig. 2 is likewise a longitudinal vertical, central section of the steam-chest, showing the piston nearing the opposite end of its stroke and the valve and all its parts 45 nearing a position to admit steam to the rear end of the engine-cylinder and to open the exhaust for the expulsion of the spent steam in the forward end of the cylinder upon the return stroke of the piston. Fig. 3 is a trans- 50 verse vertical section through the steam chest and valve on dotted line $x-x$ of Fig. 2, showing the auxiliary exhaust-ports. Fig. 4

is a side elevation of the supporting-spider for the piston-heads of the valve. Fig. 5 is an end elevation of said spider. Fig. 6 is a 55 side elevation of one of the valve-heads. Fig. 7 is an inside face view thereof. Fig. 8 is a side elevation of one of the puppet-valves.

Like letters of reference indicate corresponding parts throughout the several views. 60

In the embodiment of this invention I provide an engine-cylinder A of ordinary construction with the usual piston B and piston-rod C, surmounting the cylinder A by a steam-chest D, having the steam-jacket D' for the 65 admission of live steam from the boiler and having also the heads D², secured to the steam-chest by tap-bolts in the usual manner. The interior of the steam-chest D is bored and counterbored as is customary in steam-chests 70 of this kind, and has communication with the cylinder by the ports A' and A² and with the outer air by the exhaust-port A³.

E is the valve-spider, composed of the hub E', the radially-extending web-arms E², the 75 rims E³, and the annular end rings E⁴ and E⁵. The annular rings E⁴ and E⁵ are separated from the rims E³ by the lugs E⁶, forming at either end of the spider the auxiliary ports E⁷ and E⁸. The ring E⁴ and the adjacent rim 80 E³ and the ring E⁵ and its adjacent rim E³ are provided with the packing E⁹, fitting the spider to the bore of the steam-chest D, which packing is cut away opposite the auxiliary ports E⁷ and E⁸. The hub E' is provided with 85 a longitudinal central opening E¹⁰, extending therethrough.

The tapering puppet-valves F and F' are seated in the annular rings E⁴ and E⁵, respectively, of the valve-spider E. These puppet-valves are provided with stems F² and F³, respectively, extending inward within the 90 central opening E¹⁰ of the spider E, which said stems are of such a length that when one of said puppet-valves is closed upon its seat 95 the other valve is forced open by the engagement of the stems of said valves. The closure of the puppet-valve F closes the auxiliary ports E⁷, and the closure of the puppet-valve F' closes the auxiliary ports E⁸. The 100 puppet-valve F, and consequently the auxiliary ports E⁷, are closed during the rearward stroke of the piston B, and the puppet-valve F' and the auxiliary ports E⁸ are then open

for the passage of the exhaust. The puppet-valve F and the auxiliary ports E⁸ are closed during the admission of steam through the port A' to the rear end of the cylinder A, and at such times the puppet-valve F and the auxiliary ports E⁷ are open to the exhaust. The helical springs F⁴ and F⁵ surround the stems F² and F³ of the puppet-valves and cushion the closing of said valves, as well as assisting in the opening thereof. The puppet-valves F and F' are provided with the central outwardly-extending pistons F⁶ and F⁷, respectively, the purpose of which will be later described herein.

15 The piston-heads G and G' of the valve are rigidly secured by means of the bolts G² to the annular rings E⁴ and E⁵, respectively, of the valve-spider E, which piston-heads are provided with the packing G³ to make them 20 tight with the bore of the steam-chest D. Each piston-head is also provided with the circumferential groove G⁴ and the transverse peripheral grooves G⁵, which latter grooves extend, as well, across a portion of the 25 peripheral faces of the annular rings E⁴ and E⁵, respectively, communicating with the circumferential grooves G⁴. The openings G⁶ in the faces of the piston-heads G and G' communicate through the openings G⁷ with the 30 circumferential grooves G⁴ and form means of access for the live steam to the chambers H and H' over the puppet-valves F and F'. The piston-head G has a rigid connection with the valve-rod G⁸ and is provided with 35 the central opening G⁹ for the reception of the piston F⁶, forming a small cylinder in which said piston fits tightly. The opening G⁹ is provided with the inlet G¹⁰ for the admission of live steam to the closed end of 40 said opening G⁹. The similar opening G¹¹ is provided in the piston-head G' as a cylinder for the reception of the piston F⁷, and this opening also has the aperture G¹² for the admission of live steam to the closed end of the 45 opening G¹¹.

The operation of this valve is as follows, having reference to Fig. 1, wherein the parts are represented as occupying such relative positions that live steam within the steam-chest D would be free to pass through the port A² into the cylinder A, in the clearance-space in front of the piston B. The pressure of this steam exerted upon the front of said piston pushes it backward in the cylinder A, also opening the port A² by driving the valve in the same direction as that pursued by the piston. Live steam also enters the openings G⁷ and G⁶ in the piston-head G, holding the puppet-valve F firmly against its seat in the 50 annular ring E⁴, in which it is also assisted by the pressure of the live steam upon the piston F⁶, formed integral with the puppet-valve F, which steam enters the opening G⁹ through the passage G¹⁰. This closing of the 55 puppet-valve F and the auxiliary ports E⁸ opens the puppet-valve F' and the auxiliary ports E⁷, and the rearward movement of the 60

steam-valve opens the port A' into the port A³, permitting the air in the rear end of the cylinder A to be from thence discharged. 70 When the piston nears the rear end of the cylinder A, the parts assume the positions as indicated in Fig. 2, where the exhaust through the port A' is suspended and the air or steam within the rear end of the cylinder A is being 75 compressed before the backward-moving piston B. This compressed air or steam entering the chamber H' through the grooves G⁴ and G⁵ in the periphery of the piston-head G' and the openings G⁶ and G⁷ in its interior, 80 sharply closes the puppet-valve F' against the cushioning effect of the spring F⁵, at the same time opening the other puppet-valve F. This also opens the auxiliary ports G⁷ for the 85 passage of the exhaust from the forward end of the cylinder as soon as the movement of the steam-valve places the port A² into communication with the exhaust-port A³ and opens the port A' for the admission of live steam into the rear end of the cylinder A. 90

I claim as my invention—

1. In a steam-engine valve, in combination, a steam-chest having steam-ports and an exhaust-port communicating with the interior of the steam-chest; a reciprocatory valve-spider therein, having an auxiliary port in each of its ends; and a valve for each of said auxiliary ports, one of which valves has a stem fixed thereto adapted to actuate the other valve, which said stem is of such length 95 that one of said valves is opened when the other valve is closed.

2. In a steam-engine valve, in combination, a steam-chest having steam-ports and an exhaust-port communicating with the interior 105 of the steam-chest; a valve-spider having a longitudinal opening therein, and being provided with an auxiliary steam-port at each of its ends; and a valve for each of said auxiliary ports, each of which valves has a stem 110 fixed thereto, adapted to lie within the longitudinal opening in said valve-spider, which stems are of such length as to engage each other and cause one of said valves to be opened when the other is closed. 115

3. In a steam-engine valve, in combination, a steam-chest having steam-ports and an exhaust-port communicating with the interior 120 of the steam-chest, a reciprocatory valve-spider having an auxiliary port at each end 125 of said spider, a valve for each of said auxiliary ports, one of which valves is adapted to have an engagement with the other valve, and a piston-head for each end of said spider, each of which piston-heads has an opening 130 extending from its periphery to a point in its face.

4. In a steam-engine valve, in combination, a steam-chest having steam-ports and an exhaust-port communicating with the interior 130 of the steam-chest, a reciprocatory valve-spider having an auxiliary port at each of its ends and a longitudinal opening, a valve for each of said auxiliary ports, each of which

valves has a stem adapted to extend within the longitudinal opening in said spider and an oppositely-extending piston, and a piston-head secured to each end of said spider, each of which piston-heads has an opening extending from its periphery to a point in its face, and a cylinder-opening for the reception of the piston on one of said valves.

5. In a steam-engine valve, in combination, a steam-chest having steam-ports and an exhaust-port communicating with the interior of the steam-chest, a reciprocatory valve-spider having an auxiliary port at each end of said spider, also having a longitudinal central opening, a valve for each of said auxiliary ports, each of which valves has a stem

adapted to lie within the opening in said valve-spider and an oppositely-extending piston, a spring for each of said valve-stems, and a piston-head secured to each end of said valve-spider, each of which piston-heads has a circumferential groove, an opening extending from said circumferential groove to a point in its face, a cylinder-opening for the reception of the piston of one of said valves, and an opening communicating between the interior of said cylinder-opening and the interior of said steam-chest.
